(57) **CLAIM**

I claim the ornamental design for a shoe, as shown and described.

DESCRIPTION

FIG. 1 is a perspective view of a shoe showing my new design;

FIG. 2 is a right side elevational view thereof, the left side elevational view being the same as said right side elevational view; and,

FIG. 3 is a top plan view thereof.

A bottom view is not essential to my new design and would show no part of the claimed design.
